UNITED STATES PATENT OFFICE

2,446,603

WATERTIGHT WATCHCASE

Ernest Morf, La Chaux-de-Fonds, Switzerland

Application January 27, 1945, Serial No. 574,849
In Switzerland October 23, 1944

1 Claim. (Cl. 58—90)

1

This invention relates to watertight watch-cases.

There are watertight watch-cases, the center and bottom of which are in one piece, in that they are either forced into each other or welded together, or made in one piece with each other. In such watches, a crystal of plastic material is forced into the combined center and bottom. Since in this case the quality of tightness depends on the pressure exerted on the inner walls of the combined center and bottom by the crystal of plastic material, and since, therefore, the crystal is given the greatest possible elasticity, removal of this crystal is so difficult that, in spite of special precautions taken, it is very often damaged during this operation.

The object of the invention is to create a watch-case in which this danger of damaging the crystal does no longer exist. Besides this, the characteristics of the invention allow various other advantages to be obtained, as will be seen later on.

The watertight watch-case according to the invention comprises a crystal with a sleeve forced into the combined center and bottom and is characterised in that this crystal has a circumferential flange extending towards the outside of the watch-case and overlapping a joint formed between a thinned rim of the combined center and bottom and a caseband adjusted to this thinned rim.

The accompanying drawing illustrates, by way of example, one embodiment of the watertight watch-case according to the invention.

The single figure is an axial section through this embodiment.

Referring now to the drawing, the combined center and bottom is designated by 10. It has, as usual, a flange 11 on which the plate of a watch movement (not shown) is supported. The upper part of the member 10 has a rim 12 into which a sleeve 13 is forced, obtained by moulding and made in one piece with the crystal 14. An elastic ring 15 compensates, by pressing upon the sleeve 13, an eventual fatigue of the latter.

The combined bezel and caseband 16, to which

2

the lugs 17 are fixed, comprises a flange 18 bearing against the thinned rim 12. A shoulder 19 is provided beneath the member 16 on the combined center and bottom 10, against which for instance the blade of a knife can be inserted for separating the two pieces from each other. And since the crystal 14 overlaps the joint between the flange 18 and the rim 12 by a flange 7 outside the sleeve 13, the crystal can be removed by acting upon the combined bezel and caseband 16 in order to separate it from the combined center and bottom 10. In this way the watch-case can be completely taken to pieces for removing the movement without touching the crystal, thus avoiding any damage of the latter.

I wish it to be understood that I do not desire to be limited to the exact details of construction shown and described, for obvious modifications will occur to a person skilled in the art.

20 What I claim is:

In a watch-case, a combined center and bottom comprising a thinned upper rim and a shoulder, a crystal having a sleeve forced into said upper rim, a caseband supported on said shoulder and surrounding said thinned upper rim, said crystal having a flange outside said sleeve, covering said thinned upper rim and at least a part of said caseband, said combined center and bottom comprising a second shoulder beneath said caseband to allow a tool to be supported thereon for attacking said caseband to remove said crystal.

ERNEST MORF.
